UNITED STATES PATENT OFFICE.

KAYSEE FORTENBERRY, OF CHICAGO, ILLINOIS.

ELECTRICAL HAIR COMB.

Application filed June 17, 1925. Serial No. 37,830.

This invention relates to new and useful improvements in combs and more particularly to an electrically heated comb. The main object of my invention is the provision 5 of a special type of comb which is electrically heated and preferably used for straightening the hair.

Another object of my invention is the provision of an electrically heated comb where- 10 by the device is so constructed as to readily heat the teeth of the comb and in providing the teeth of curved formation whereby when these curved teeth are drawn thru the curled hair, it will not only heat the hair but have 15 a tendency to straighten the same.

A further object of my invention is the provision of an electrically heated comb whereby parts are so constructed that they may be readily taken apart or put together 20 with ease when so desired.

With the above and other objects in view, my invention consists in the novel features of construction and the combination and arrangement of parts to be hereinafter more 25 fully described, pointed out in the claims and shown in the accompanying drawings, in which:

Fig. 1 is a side elevation of a comb constructed in accordance with my invention, 30 Fig. 2 is a longitudinal sectional view, and

Fig. 3 is a transverse sectional view on the line 3—3 of Fig. 2.

In carrying out my invention I provide 35 a tubular body member 1 having a longitudinal slot 2 upon one side thereof, with one end of the body closed. Arranged in the body is a cylindrical core 3 upon which the heating coil 4 is wound, said coil being 40 connected to the current supply wires 5 in any suitable manner.

Fitted into the open end of the body 1 is a reduced shoulder portion 6 of the handle 7 and the handle is provided with a central bore 8 through which the wires 5 extend before being connected to the heating coil 4. The end of the body 1 is retained upon the shoulder 6 by means of a set screw 9 whereby the tubular body may be removed from the 50 handle when so desired.

The teeth used in my improved comb are formed integral with the body portion 10 which has divergent flanges 11 arranged in the tubular body 1 and in contact with the heating coil 4, the body of the comb being 55 placed in position by sliding the same in the

slot 2 with the flanges 11 fitting between the interior of the body and the heating coil. It is important to note that when the handle 7 is mounted with its shoulder in- 60 inserted in the tubular body 1 that the handle serves to obstruct the entrance of the slot 2 to prevent self-displacement of the comb body.

The teeth of the comb are arcuately 65 curved as shown at 12 and tapered longitudinally of their length and have their outer ends curved in a direction opposite to the curvature 12 as shown at 13 which construction will have a tendency to more 70 thoroughly straighten the hair than with an ordinary straight tooth comb, due to the fact that as the hair rides over the curved portion 12 it will become thoroughly heated and straighten to a slight degree and when 75 it reaches the outer ends of the teeth which are curved opposite the curvature 12 the teeth will have a tendency to turn the hair in a direction opposite the natural curl and thus have a tendency to cause the hair to 80 straighten out more thoroughly.

From the above it will be apparent that I have provided a simple and inexpensive electrical comb which is especially adapted 85 for use in straightening very curly hair and by passing the teeth of the comb through the hair in a manner whereby the curled hair will ride over the curved portions 12 and 13 and at the same time become thoroughly heated, it will have a tendency to 90 cause the hair to straighten out. The device is so arranged that it may be readily taken apart or put together when so desired.

As shown in Figs. 2 and 3 of the drawing the upper end portions of the teeth of 95 the comb are separated by humps 4' which contact directly with the heating element 4. The humps are defined on opposite sides of air pockets 5' formed in the upper end portions of the teeth. By forming these air pockets the material forming the upper end portions of the teeth is diminished thereby facilitating rapid heating of the teeth and permitting the hot air created by the heating element to accumulate at the upper end 100 portions of the teeth.

It will be apparent that the teeth of the comb are formed of metal and has the flanges 11 which when they are in direct contact with the heating coil, the teeth will 110 be readily heated.

While I have shown and described the

preferred form of my invention, it will be obvious that various changes in the details of construction and in the proportions may be resorted to for successfully carrying my invention into practice without sacrificing any of the novel features or departing from the scope of the appended claims.

Having thus described my invention, what I claim is:

10 1. An article of the class described including a tubular body having a longitudinally extending slot formed therein, a heating element confined in the body, a comb body defining portions slidably mounted in the slot 15 and provided with diverging portions disposed within the tubular body directly in contact with the heating element, teeth defined by the comb body, and humps formed at the upper end portion of the teeth for

disposing the teeth in spaced relation with respect to each other, said humps being adapted for direct contact with the heating element.

2. An article of the class described including a tubular body having a longitudinally extending slot formed therein, a heating element confined in the body, a comb body having portions slidably received in the slot, teeth defined by the body, and humps formed at the upper end portions of the teeth for disposing the teeth in spaced relation and adapted for direct contact with the heating element, there being air pockets defined at the upper end portion of the teeth between said humps.

35 In testimony whereof I affix my signature.

KAYSEE FORTENBERRY.
